UNITED STATES PATENT OFFICE.

LAWRENCE J. WILLNER, OF DULUTH, MINNESOTA.

VALVE-GEAR FOR ENGINES.

1,159,145.

Specification of Letters Patent. Patented Nov. 2, 1915.

Application filed April 22, 1915. Serial No. 23,161.

To all whom it may concern:

Be it known that I, LAWRENCE J. WILLNER, a citizen of the United States, residing at Duluth, in the county of St. Louis and 5 State of Minnesota, have invented certain new and useful Improvements in Valve-Gears for Engines, of which the following is a specification, reference being had therein to the accompanying drawing.

10 My invention relates to improvements in valve gears for engines especially to that form of gear known as the link motion for steam engines, wherein the cut-off may be varied and the engine reversed thereby.

15 Another object of the present improvement is to devise a valve gear constructed in such a manner that the link may be operated by one eccentric instead of by the use of two as has heretofore been necessary.

20 Other objects and advantages of the present improvement will be set forth in the following description and drawing in which the figure is a diagrammatic view showing a front elevation of my improved gear.

25 The application and advantages of a link-motion valve gear to a reciprocating engine is well established and understood in the art, and the invention herein resides only in the novel combination of parts herein- 30 after disclosed.

Referring now to the drawing in detail in which like reference numerals designate similar parts, 1 represents the crank shaft of an engine, and 2 the slide valve within 35 the steam-chest of the said engine which valve governs the supply of steam to the engine in the usual and well known manner.

38 represents the usual form of eccentric fixed to the shaft 1 in the usual manner and 40 surrounded by an eccentric strap comprising the halves 4 and 5. Upon the uppermost half 4 of the strap an eccentric rod 6 is rigidly fixed which extends upwardly and is pivotally connected at 7 to a link 8. The 45 link 8 is of the common form and manually controlled in the usual manner, its connection to the valve 2 being the stem 2'.

The half 4 of the eccentric strap is provided with an ear 9 forming a pivotal point 50 which ear is positioned on the strap at substantially thirty-seven degrees from the center line of the rod 6. A rod 10 has one end pivotally connected to the ear 9 and its other end connected to one arm 11 of a bell crank, said bell crank being pivotally mounted upon a fixed bearing 13. The bear-

ing 13 may be supported from the engine frame in any desired manner. The other arm 12 of the bell crank is pivotally connected at its free end to a rod 14. The upper end of the rod 14 is pivotally connected at 15 to the link 8 at the opposite end thereof to that at which the rod 6 is attached.

From the above it is apparent that the link 8 is supported and controlled in every 60 particular in a manner customary in such devices except that it is operated from but a single eccentric instead of by two eccen- 65 trics as has been done heretofore.

The connection of the half 4 of the eccen- 70 tric strap at the point 9 through the medium of the rod 10, bell crank 11—12 and rod 14, imparts motion to one end of the link 8 whereby the same results are accomplished as with the ordinary two eccentric link- 75 motion valve gear used only with one eccen- tric.

It is evident that the arrangement of rods operating the different ends of the link may be transposed to suit convenience in 80 the construction of the engine.

Having thus fully described my invention what I claim and desire to secure by Letters Patent is:

1. A link-motion valve gear for engines, 85 comprising an eccentric fixed to the crank shaft of the engine, a strap surrounding the eccentric, a rod rigidly fixed to the strap and directly connected to one end of the link, a second rod pivotally connected to the ec- 90 centric strap adjacent the first-mentioned rod and indirectly connected to the opposite end of the link, whereby the link is recipro- 95 cated by the revolving of the crank shaft and the valve of the engine controlled in the usual manner.

2. A link-motion valve gear for engines, 100 comprising an eccentric fixed upon the crank shaft of the engine, a strap surrounding the said eccentric, a rigid connection between the strap and one end of the link, a movable connection between the eccentric and the other end of the link, a connection between the link and the valve gear of the engine, whereby the link is reciprocated and the 105 valve of the engine controlled by the revolutions of the crank shaft.

3. A link-motion valve gear for engines, 110 comprising an eccentric mounted upon the crank shaft of the engine, a strap surround- ing the said eccentric, a link, a connection between the link and the valve of the en-

gine, a rigid connection between the upper face of the strap and one end of the link, a movable connection between the upper face of the strap and the other end of the link, the said movable connection arranged at an angle of thirty-seven degrees to that of the rigid connection, the said link being reciprocated and the valve controlled by the revolutions of the crank shaft.

4. A link-motion valve gear for engines, comprising an eccentric fixed upon the crank shaft of the engine, a strap surrounding the said eccentric, a link, a connection between the link and the valve of the engine, a rod rigidly fastened to the upper face of the eccentric and having its other end pivotally connected to one end of the link, a lever having one end pivotally connected to the upper face of the strap, a second lever having one end pivotally connected to the opposite end of the link to that at which the rigid rod is pivoted, and means connected to the free ends of the said levers whereby the movement of one lever in one direction causes the other lever to move in the opposite direction, the link being reciprocated and the valve of the engine controlled by the revolutions of the crank shaft.

5. A link-motion valve gear for engines

comprising an eccentric fixed to the crank shaft of the engine, a strap surrounding the said eccentric, a link, a connection between the link and the valve of the engine, a rod having one end rigidly connected to the strap and its other end pivotally connected to one end of the link, an ear pivotally mounted upon the strap, said ear arranged thirty seven degrees from the center line of the said rod, a lever having one end pivotally connected to the said ear, a second lever having one end pivotally connected to the link at the opposite end to that to which the end of the rod is pivoted, a bell crank pivotally carried by the framework of the engine, and having its arms pivotally connected to the free ends of the said levers whereby the movement of the rod to impart a motion in one direction to the link, and the levers through the medium of the bell crank to impart the opposite motion to the link, the parts arranged as and for the purpose described.

In testimony whereof I hereunto affix my signature in the presence of two witnesses.

LAWRENCE J. WILLNER.
